(57) **CLAIM**

The ornamental design for an electric toothbrush, as shown and described.

DESCRIPTION

FIG. 1 is a perspective view of our new design; FIG. 2 is a left side elevational view of our new design, the right side elevational view of our new design being a mirror image thereof;

FIG. 3 is a front elevational view of our new design;

FIG. 4 is a rear elevational view of our new design;

FIG. 5 is a top plan view of our new design; and,

FIG. 6 is a bottom plan view of our new design.

The broken line showing of portions of the electric toothbrush is for illustrative purposes only and forms no part of the claimed design.
